UNITED STATES PATENT OFFICE.

THOMAS CRICK, OF INDEPENDENCE, MISSOURI, ASSIGNOR TO INDEPENDENCE STOVE AND FURNACE COMPANY, OF INDEPENDENCE, MISSOURI, A CORPORATION OF MISSOURI.

FURNACE.

Application filed March 27, 1922. Serial No. 547,164.

To all whom it may concern:

Be it known that I, THOMAS CRICK, a citizen of the United States, residing at Independence, in the county of Jackson and 5 State of Missouri, have invented a certain new and useful Improvement in Furnaces, of which the following is a specification.

My invention relates to improvements in furnaces. It relates particularly to hot air 10 furnaces of the type in which the combustion chamber discharges into a radiator, the flue of which is arranged so as to be accessible, for the purpose of easy cleaning, through the fuel passage which connects 15 the combustion chamber with the outer casing of the furnace.

It has been customary in furnaces of this type to rigidly connect the radiator with the fuel passage, by bolting or by making 20 the radiator integral with the fuel passage. This is objectionable in that, owing to the greater heat to which the radiator is subjected, the unequal expansion and contraction of the radiator and feed 25 passage is liable to crack the parts or sever the connecting bolts.

One of the objects of my invention is to provide a construction in which the radiator is free to expand or contract independently 30 of the fuel passage or the combustion chamber, thereby avoiding liability to fracture or shearing of bolts, while retaining the advantage of easy cleaning of the radiator through the feed passage, and at the same time affording a construction which is simple, cheap to make, and which may 35 be readily assembled and disassembled.

A further object of my invention is to provide novel means for tightly sealing 40 where the radiator abuts against the fuel passage and the combustion chamber.

Still another object of my invention is to provide a construction of the type described 45 in which the line of contact between the combustion chamber and the fuel passage with the radiator is of minimum extent, thus affording a putty seat of minimum length and reducing liability of leakage of gas and smoke.

50 The novel features of my invention are hereinafter fully described and claimed.

In the accompanying drawings, which

illustrate the preferred embodiment of my invention,

Fig. 1 is a side elevation of a portion 55 of a furnace provided with my improvements, the outer casing being omitted.

Fig. 2 is a front elevation of what is shown in Fig. 1.

Fig. 3 is a vertical sectional view on the 60 line 3—3 of Fig. 2, a portion of the outer casing being shown.

Fig. 4 is a top view of what is shown in Figs. 1 and 2.

Fig. 5 is a top view of the combustion 65 chamber and fuel passage.

Fig. 6 is an under view of the radiator.

Fig. 7 is a side elevation showing the radiator raised clear of the combustion chamber and fuel passage.

Similar reference characters designate 70 similar parts in the different views.

1 designates the body of the combustion chamber, mounted in the usual manner on a fire bowl 2. The combustion chamber 75 has a front feed opening 3, and about the opening 3 it has a tubular extension 4, preferably integral with the body 1, and which forms a fuel passage. The front end of the extension 4 may be attached in any 80 well known manner to the front plate 5' of the outer casing, Fig. 3.

The extension 4 is provided at its top and front end with a raised portion 5. The body 1 and extension 4, at the rear of the 85 raised portion 5, is provided with a top opening 6. The body 1 and extension 4 and raised portion 5 is provided around the opening 6 with a continuous groove 7 which forms a continuous putty seat.

8 designates a radiator, preferably circular, and which is provided with a flue comprising a radial portion 9, the outer end of which discharges into an annular horizontal flue portion 10, which at its rear end discharges through a pipe collar 11 on the rear of the radiator.

The bottom of the radiator 8 is provided with an opening 12, Fig. 6, which preferably extends through the front side and 100 lower portion of the radiator, and which communicates with and is substantially the same size and shape as the opening 6.

The lower side of the radiator 8 about the

opening 12 has a continuous flange portion 13 which rests in the putty seat 7, and which is embedded, when in operative condition, in putty contained in said seat. The rear 5 end of the raised portion 5 of the fuel passage extends into the opening 12 in the side and bottom of the radiator.

The radial portion 9 of the radiator flue forms in substance an extension of the combustion chamber. The gaseous products pass from the combustion chamber 1 through the opening 6 into the radial portion 9 and thence to the smoke pipe, not shown, through the annular portion 10 and the collar 11.

15 With the construction shown and described, easy access to the radial portion 9 and annular portion 10 of the radiator flue may be had through the fuel passage, for the purpose of cleaning the radiator flue, the 20 soot being dropped from the flue directly into the combustion chamber and extension 4.

It will be noted that the radiator merely abuts against the putty in the putty seat 7 25 of the extension 4, and that it has no binding connection therewith or with the front plate 5' of the outer casing. The radiator is thus free to expand and contract independently of the extension 4, thus avoiding 30 liability of fracture of the parts or of shearing or breaking of connecting bolts.

With the construction shown and described, a simple structure of few parts is afforded, which is readily assembled, which 35 is durable and not liable to damage by expansion and contraction of the parts, and in which the single feed passage affords the further function of ready access to the radiator flue.

40 I do not limit my invention to the structure shown and described, as many modifications, within the scope of the appended claims, may be made without departing from the spirit of my invention.

45 What I claim is:—

1. In a furnace, a combustion chamber having an opening and a tubular extension about said opening forming a fuel passage, the extension having a raised portion at its 50 top and front, and a radiator having a flue into which said chamber discharges and having an opening in its bottom and in one side directly connecting said flue with said passage, said raised portion of said extension at its rear end extending into said opening in the side of the radiator, substantially as set forth.

2. In a furnace, a combustion chamber having an opening and a tubular extension 60 about said opening forming a fuel passage,

the extension having a raised portion at its top and front, said raised portion having an open rear end, and a radiator having a flue into which said chamber discharges, the bottom of the radiator having an opening 65 extending through one side of the radiator and connecting directly said flue with said combustion chamber and with said passage at the rear of said raised portion, the upper end of the combustion chamber and the top 70 of said extension at the rear of said raised portion having an opening of substantially the same size as and registering with the opening in the bottom of said radiator, substantially as set forth.

3. In a furnace, a combustion chamber having an opening and a tubular extension about said opening forming a fuel passage, the upper side of said chamber and said extension around said opening having a continuous putty seat, and a radiator having a flue 80 comprising a radial portion and an annular portion into which said radial portion discharges, the bottom of said radiator being fitted in said seat and being provided with 85 an opening of substantially the same size as and registering with the opening in the upper end of the combustion chamber and in the top of the extension and directly connecting the latter opening with said radial 90 and annular portions of the radiator flue, substantially as set forth.

4. In a furnace, a combustion chamber having an opening and a tubular extension about said opening forming a fuel passage, 95 said extension having at its top and front a raised portion, the upper end of the combustion chamber and the top of said extension at the rear of said raised portion having an opening, the upper end of the combustion chamber and the upper side of said extension around said opening having a continuous putty seat, and a radiator having its lower end fitted in said seat and provided 100 with a flue comprising a radial portion and 105 an annular portion into which the radial portion discharges, the bottom of the radiator having an opening which extends through one side of the radiator and which directly connects said radial and annular 110 portions with the opening in the top of the combustion chamber and said extension, the rear end of said raised portion of said extension being open and communicating 115 through the opening in the side of the radiator with said annular and radial portions, substantially as set forth.

In testimony whereof I have signed my name to this specification.

THOMAS CRICK.
